UNITED STATES PATENT OFFICE.

JOHN T. ROWLEY, OF TYRONE, PENNSYLVANIA, ASSIGNOR TO THE KEY-STONE AXLE COMPANY, OF WHEELING, WEST VIRGINIA.

MACHINE FOR SHAPING IRON OR STEEL.

SPECIFICATION forming part of Letters Patent No. 566,701, dated August 25, 1896.

Application filed June 13, 1896. Serial No. 595,441. (No model.)

To all whom it may concern:

Be it known that I, JOHN THOMAS ROWLEY, a citizen of the United States, residing at Tyrone, in the county of Blair and State of Pennsylvania, have invented certain new and useful Improvements in Machines for Shaping Iron or Steel, of which the following is a specification.

My invention has reference to improvements in machines for converting cylindrical bars into desired shapes suited for various purposes, one purpose being for car-axles. On the 3d day of February, 1891, Letters Patent of the United States No. 445,662 were granted me for improvements in machinery for shaping iron or steel axles. My present invention is an improvement on that machine.

The invention is illustrated in the accompanying drawings, in which—

Figure 1 shows three views illustrating, first, the cylindric bar or blank before entering the machine; second, the appearance of the same when it has passed about half-way through the forming-pass, and, third, the finished axle as it leaves the machine. Fig. 2 is a plan or top view of the machine. Fig. 3 is a front side elevation of the machine. Fig. 4 is an end elevation of same. Fig. 5 is a vertical cross-section showing the roller, concave, removable concave die, and forming-pass. Figs. 6, 7, and 8 show different positions of the removable concave die-plate. Figs. 9 and 10 show one of the fastening blocks and wedges, respectively.

The main body of the machine comprises two parts or halves, each of which embraces a flat or horizontal base A, a vertically-placed concave back H², end housing A' for the journal-boxes e, a brace-web A² at the rear of the concave back and uniting with the flat base, a curved flange A³ also at the rear of the concave back and joined to the said base, and a bolt-flange A⁴ on the base at the front. The back H² of these two half parts is concaved on its front side in the form of a half-cylinder, which stands vertically. Each half part is a single casting and constitutes one end of the body, and the said two half parts are joined by the two curved flanges A³, being secured together by bolts a, and the front flange A⁴ by bolts a'. Thus the two solid

ends of the body of massive cast metal are separated and joined on a central vertical line crosswise of the concave. This construction of the body results in great solidity and strength and has other advantages herein-after pointed out. The cylindric roller C has its journals mounted in the boxes e, which enter sidewise to the seats e in the end housings A'. A vertical bar j is in front of each end housing and confines the said box and is secured firmly by horizontal bolts j'. The vertical wall at the inner side of the end housing has a projecting tongue l, which curves coincidently with the half-cylinder concave. This tongue is indicated by broken lines in Fig. 4, and the lower end of each tongue may be seen in Fig. 3. A removable concave die-plate N is made in sections, in the present instance five sections, and has on each curved end a groove l'. (See Figs. 6 to 8, also Fig. 3.) When the die-plate is in position, its grooves l' are occupied by the said tongues l. The back side of this concave die-plate conforms to the shape of and fits against the said fixed concave back H², and the top edge or entrance edge m of the removable concave die-plate fits against a fore plate k, which is secured by bolts k' to front and top of the concave back. (See Figs. 3 and 5.)

To retain the removable concave die-plate N in position, the top surface of the base at the front is provided with two sockets q (indicated by broken lines) and also with two upward-projecting lugs r in front of said sockets. A fastening-block q' has on its lower side a boss q², which latter enters said socket q, while the front edge of the block abuts against one of the lugs r. This construction makes the fastening-block very stable and firm. A wedge s is then forced between the said block and the lowermost or terminal edge o' of the die-plate. The two blocks q' and the two wedges retain said die-plate securely.

In order to remove the sections of the die-plate N when worn out and replace the same with new sections, the two half parts of the body are to be disconnected by removing the bolts a' and separating the said half parts. A new set of section-plates N may then be adjusted to their position on the tongues l, and then the said half parts again bolted together.

The described construction of the body in two parts separated on a central vertical line affords the advantage here referred to. The sections of the die-plate N extend across and 5 cover the central vertical joint.

The roll C has a swelled middle n, similar to the roll in the formers of my patent referred to. This roll also has at each end enlargements or collars i, similar to those on 10 the roll in the second set of formers of said patent. Thus in my present invention one roller has the two features together which in my said patent are separately placed on two different rollers. This arrangement of the 15 cylindric roller is made feasible and practicable by the construction here shown of die- surface on the concave plate N. The concave die-plate N at the entrance end m is straight, (see Figs. 3 and 6,) but a little below 20 said edge the middle swell n', corresponding to the swell n on the cylinder-roll, begins to form. This middle swell has a uniform breadth, but gradually increases in thickness or depth from the starting-point to the center 25 of the concave, a distance sufficient to cause the axle-blank, in traversing the pass between the roll and concave die, to be rotated at least once or perhaps more on its own axis. The center of the concave die-plate is 30 seen in Fig. 7. The middle swell n on the roll and n' on the concave serve to reduce the cylindric bar or blank from the form seen in the first view x of Fig. 1 to the reduced form y' seen in the second view of the same figure. 35 Some of the concave die-sections also have at each end raised formers i', corresponding to the collars i on the roll. These formers commence at the center section or a little before the center, and continue to the terminal edge 40 or delivery edge o' of the last section. From the center of the concave plate N to the delivery edge o' the middle swell n' continues full thickness. The raised formers i' and collars i serve to impart to the axle-blank the reduced 45 shapes at each end, which are the journals, and the parts described all together give the finished axle shape z. (Seen in the third view of Fig. 1.) From the foregoing it will be seen that the die-surface of concave plate N has its 50 first half (commencing at entrance edge m) provided only with a middle swell n', gradually increasing in thickness and its latter half provided with raised formers i' and also with the full thickness of middle swell. It is this construction of die-surface that enables the use 55 of one cylinder-roller which has on it both middle swell and end collars. It is proper to state that this machine, like that shown in my patent referred to, requires that the relation of 60 the roll C and concave die-surface shall be such as to form a pass that is wider at the entrance end than the delivery end, so that as the blank bar of metal traverses this pass it will be somewhat reduced in diameter. 65 A feed-guide to direct the hot cylindric bars into the pass o comprises two inclined bars t, one at each side, each bar having its upper

end secured by a bolt u or other means to the vertical bar j. The lower end of these inclined bars rest upon the cylindric roll. When 70 the heated blank bar is dropped onto these inclined bars t, it is guided into the pass.

It will be seen that in this machine the cylindric roll is horizontal and the concave die-plate N is at the vertical side of the roller 75 and not below it, as heretofore. The entrance to the pass is therefore on top or directly above the roller, and the discharge end of the pass is centrally under the roller. The open pass o thus describes a segment of a circle 80 standing vertically on one of its ends. This arrangement and construction results in practical advantages. One advantage is that the hot blank may be dropped directly on top of the constantly-moving roller C and rest thereon bodily, and the roller by its movement will carry the hot blank to the entrance of the pass, and as the blank strikes against the edge m of the concave die said blank will be sure to enter the pass in true parallel position. Another advantage which results is that the weight or gravity of the hot blank assists to carry it downward through the pass and out, and still another important advantage is that the metallic scale, which drops 85 from the blank in the process of rolling, will slide out of the pass instead of remaining therein and accumulating, as it will do where the concave is wholly below the roller, as, for instance, is the case of my patent already referred to. By thus providing for the refuse scale to freely slide out of the pass o said pass is kept clear of this objectionable debris.

From the foregoing description the operation of the machine will be understood. 105

It is necessary to have the die-surface in good condition, and I have therefore provided for renewing this surface by the present construction of removable sections of concave plate N. When the die-surface becomes worn so as to be no longer capable of doing good work, all the sections may be removed and new ones inserted. As the die-surface of the plate wears it becomes thinner, and as the roller wears it also becomes smaller. The pass 110 through which the axle-bar must travel will thereby become gradually enlarged until it is unsuited for use. To provide for this wear, I make use of a number of thin plates p p'. At the outset, when the roller and die-surface 115 are new, several of these plates p, say three or four, are placed under the journal-box e, and a like number of plates p' are placed at one of the vertical delivery sides of said box, as shown in Fig. 4. Now when the roller and die-surface have worn so as to make the pass o larger than it should be, then the position of the boxes e, and consequently of the roller, may be changed a little to restore the delivery end of the pass to the smaller size it had 120 before it was enlarged. This may be done by removing one liner-plate p from under the box and removing one liner-plate p' from one vertical side of the box and placing it at the 125

other side. This has the effect on the roller to both lower it and also shift it laterally toward the concave, and thereby reduce the size of the pass σ . This may be repeated as 5 the parts wear by shifting one liner-plate at a time until all have been shifted.

Having thus described my invention, what I claim is—

1. In a machine for shaping iron or steel axles, the combination of a body comprising a horizontal base, A, two end housings, A', a vertically-placed concave back, H², connecting integrally with the said base and end housing, and two central vertical flanges, A³, 15 at the rear of said concave back—said body being divided into two separable end parts on a central vertical line or joint between the said two vertical flanges; said line of separation extending vertically across the said 20 concave back; a cylindric roller placed horizontally and having its journals in said end housings—said roller provided with a swelled middle extending entirely around it; and a concave die-plate at the vertical side of the 25 roller and fitted in said concave back and covering the said central vertical joint therein, as shown and described.

2. In a machine for shaping iron or steel axles, the combination of a cylindric roller placed horizontally in suitable bearings and provided with a swelled middle extending entirely around it; a concave die-plate half cylindric standing on one of its ends at the

vertical side of the said roller, and forming a pass whose entrance end is directly on top or 35 above the roller and whose discharge end is centrally under the roller; a base and back supporting said concave die-plate; and inclined bars, t, having their lower ends in close relation with the top side of said roller. 40

3. In a machine for shaping iron or steel axles, the combination of a cylindric roller placed horizontally and provided with a swelled middle extending entirely around it; a body comprising a base, A, a concave back 45 placed vertically at the side of the said roller, and two end housings, A', each provided on its inner wall with a projecting tongue, l, curved coincidently with said concave back; a concave die-plate at the vertical side of the 50 roller—said plate provided on each curved end with a groove, l', occupied by one of said tongues; a fore plate, k, secured to the front and top of the body at the entrance edge of the die-plate; a fastening-block projecting above the top surface of the base and having a boss, q², on its under side which enters a socket in the base, and a wedge between the said block and the lowermost or terminal edge of the said die-plate. 55

In testimony whereof I affix my signature in the presence of two witnesses.
